UNITED STATES PATENT OFFICE.

FRANK W. S. ELSTROTH, OF NEW YORK, N. Y.

DOOR-HANGER.

1,027,645.

Specification of Letters Patent.

Patented May 28, 1912.

Application filed June 22, 1911. Serial No. 634,746.

To all whom it may concern:

Be it known that I, FRANK W. S. ELSTROTH, a citizen of the United States, residing in the city of New York, borough of Brooklyn, in the county of Kings and State of New York, have invented a certain new and useful Improvement in Door - Hangers, of which the following is a specification.

The invention relates to hangers in which the door or doors are suspended from carriages mounted to roll antifrictionally on fixed overhead tracks, and the object of the invention is to provide such mechanism with means for maintaining the doors against oscillatory movements, and for favorably presenting and retaining the antifriction balls in position for service.

The invention consists in certain novel features, and details of construction and arrangement by which the above objects are attained, to be hereinafter described and pointed out in the claims.

The accompanying drawings form a part of this specification and show approved forms of the invention.

Figure 1 is an elevation partly in vertical section longitudinally of the track, showing the door-suspending means. Fig. 2 is a corresponding transverse vertical section, partly in elevation. Fig. 3 is a partial plan view and horizontal section showing the ball retainer and track. Fig. 4 is a plan of the guiding means beneath the track. Fig. 5 is an end view of the track and its holding means. Fig. 6 is a vertical transverse section showing a modified form intended for light service.

Similar letters of reference indicate like parts in all the figures.

The doors are suspended from carriages B and B¹ mounted on tracks C upon antifriction balls, and having other parts and connections, to be described. Each door is supported by mechanism similar to that for the other, and either may be understood as referred to in the following description.

C is the track attached to the wall in any suitable manner, as by brackets C¹ secured by screws C² and supporting the track on a projecting lip C³. The track is fastened to the brackets by screw-bolts C⁴ extending through the track and into bosses C⁵ and each having a collar C⁶ lying against one face of the track and a nut C⁷ against the opposite face which with the bolt and boss

permit an adjustment of position relatively to the wall. The track is in the form of a light I-beam, and the upper face of the head C⁸ is planed or milled to produce a central ridge C⁹ extending its full length and joined to the remaining plane surfaces by easy curves or fillets. The under face of the base C¹⁰ is milled along the center line to produce a curved groove c, as shown.

B is the carriage, comprising also a light I-beam having its head F¹ plane on the upper face and its base F² milled on the under face similar to the track-head C⁸ to form a central ridge F³ and is provided with straps F⁴ fastened to the plane upper face of the head F¹, encircling the carriage and track with its ends extending below the latter and joined by hangers F⁵ to which the door is attached. The center lines of the hangers, track and carriage are in the same vertical plane so that torsional strains are eliminated and the centers of gravity of the carriage and suspended door lie in the plane of suspension.

A ball-retainer is interposed between the carriage and track, comprising the side-plates G¹ G¹ of sheet metal covering the space between the carriage and track and each having its upper and lower margins bent inwardly to lap upon the adjacent angular faces of the carriage base F² and track-bed C⁸. The plates are separated at suitable intervals by blocks G² G² extending across in the space between the carriage and track and held by rivets G³. The blocks are in pairs having the adjacent faces concave as at g g to form pockets in which are received pairs of balls G G separated laterally by the ridges C⁹ and F³, the curved fillets of which serve as ways for the balls which perform the function of antifriction supports for the carriage and its load. The faces of the plates are swelled outwardly as at G⁴ to form internal recesses for the outer peripheries of the balls while permitting the remaining portions of the plates to lie close to the adjacent flanges of the track and carriage.

Immediately above the hangers F⁵ is a bar D secured between the straps F⁴ by rivets D¹ and having its upper face grooved longitudinally as at d to match to the groove c in the base C¹⁰ of the track and receive a series of balls H in a second ball-holder mounted in the space between the track-base and bar

D. These balls H serve to prevent upward movements of the door and carriage relatively to the track, and also to resist side-wise movements of the door and straps relatively to the track. This second ball-holder 5 comprises an upper and lower strip H¹ H², separated by blocks H³, and having conical openings h oppositely located in each to receive portions of the upper and lower hemispheres of the balls H which protrude there-through and extend into the grooves c d as before stated. Any tendency of the door to lift or tilt is resisted by the balls H which roll antifrictionally under such strains and prevent cramping or binding. As an aid to the 10 balls H and their grooves c and d in resisting swinging movements of the door, carriage, and straps, the latter carry on the inner faces of each, vertically arranged anti-friction rollers J mounted in housings J¹ and bearing oppositely against the vertical plane 15 faces of the web C of the track. The I-beam shape of the latter providing space for such rollers without increasing the width of the 20 mechanism.

With the parts thus constructed and arranged the carriage and its suspended door are moved with a minimum of friction, and by supporting the carriage along lines passing 25 through the centers of the two parallel series of balls G G the tendency to swing is greatly reduced, and still further resisted by the lower balls H and rollers J in anti-frictional engagement with the fixed 30 track C.

The ball-retainer in which the double line 35 of balls G G is mounted is entirely self-contained, the balls cannot escape or become disarranged or misplaced either in service or when the retainer is removed, and the retainer thus constructed forms an independent member which may be introduced or removed by sliding into or out of position end-wise between the track and carriage as will 40 be understood.

Fig. 6 shows a modification intended for service with light doors. In this form the track C¹¹ is a bar having a segmental groove 45 along its upper edge, and the carriage F⁶ a similar bar having a corresponding groove along its lower edge, the two grooves serving 50 as ways for a single series of balls G⁵ mounted in a ball-retainer G⁶ analogous to the retainer for the double series first described. The straps F⁸ in this modified 55 form are joined beneath the track by hangers F⁷, and to prevent swinging movements a roller H⁴ having an annular conical flange H⁵ is mounted between the legs of the straps 60 beneath the track, with the flange engaged in a corresponding V-groove c¹ in the lower edge of the track, the roller thus serving to resist both lifting and transverse and torsional strains relatively to the fixed track. 65 G⁷ and H⁷ are projecting pins on the ball-

retainer and ball-holder, arranged to contact with the straps F⁴ which thus maintain the retainer and holder in proper relation to the carriage and track.

Other modifications may be made without departing from the invention, and parts may be used without the whole. The anti-friction rollers J may be dispensed with and the lower series of balls H relied upon to resist transverse movements, or other 70 means may be substituted for the lower series of balls to prevent lifting movements alone, with the rollers J serving to prevent swinging movements in conjunction with the wide support offered by the double series of 75 balls G G which in themselves tend greatly 80 to reduce such swinging movements.

I claim:—

1. In a door-hanger, a track, a carriage above said track, a series of balls between 85 said track and carriage, a plate on each side of said track and carriage and covering the space between them, and blocks extending from one plate to the other through said space disposed adjacent the balls and forming 90 pockets and serving with said plates to retain said balls.

2. In a door-hanger, a track, a carriage above said track, a series of balls between 95 said track and carriage and extending laterally beyond the outer lines thereof, a plate on each side of said track and carriage and covering the space between them, a recess in the inner face of each plate receiving the laterally extending overhanging 100 portions of said balls, blocks extending from one plate to the other through such space disposed adjacent the balls and forming pockets and serving with said recesses to retain said balls.

3. In a door-hanger, a track, a carriage above said track, straps on said carriage inclosing the latter and said track, a series of 105 balls between said track and carriage, and an antifriction means carried by said straps and engaged with the lower portion of said track to prevent lateral oscillations of said carriage and straps relatively to said track.

4. In a door-hanger, a track having a groove in its under face, a carriage above 115 said track, straps on said carriage inclosing the latter and said track, a series of balls between said track and carriage, and antifriction means carried by said straps and engaged in said groove whereby lateral oscillations of said carriage and straps relatively to said track are prevented.

5. In a door-hanger, a track, a carriage above said track, two series of balls arranged side-by-side between said track and 120 carriage to support the latter, and blocks forming pockets for said balls.

6. In a door-hanger, a track, a carriage above said track, two series of balls arranged side-by-side between said track and 125

130

carriage to support the latter, blocks forming pockets for said balls and means for retaining said balls in position.

7. In a door-hanger, a track, a carriage above said track, two series of balls arranged side-by-side in pairs between said track and carriage to support the latter, a plate on each side of said track and carriage and covering the space between them, a recess in each plate receiving the overhung portions of the balls of each series, and blocks extending from one plate to the other through said space and serving to hold said balls in pairs.

8. In a door-hanger, a track, a longitudinally extending ridge on the upper face thereof, a carriage above said track, a longitudinally extending ridge on the under face of said carriage, a series of balls on each side of said ridges and supporting said carriage, and means for retaining said balls in position in pairs on opposite sides of said ridges.

9. In a door-hanger, a track, a longitudinally extending ridge on the upper face thereof and a groove in the lower face, a carriage above said track, a longitudinally extending ridge on the under face of said carriage, a series of balls on each side of said ridges and supporting said carriage, means for retaining said balls in position in pairs on opposite sides of said ridges, straps on said carriage inclosing the latter and said track, a bar held by said straps beneath said track and having a groove in its upper face, and a series of balls between said bar and track and engaged in the said grooves therein.

10. In a door-hanger, a track, a longitudinally extending ridge on the upper face and a groove in the lower face thereof, a carriage above said track, a longitudinally extending ridge on the under face of said carriage, a series of balls one each side of said ridges and supporting said carriage, means for retaining said balls in position in pairs

on opposite sides of said ridges, straps on said carriage inclosing the latter and said track, and vertically arranged antifriction rollers carried by said straps on opposite sides of said track and in rolling contact with the side faces thereof.

11. In a door-hanger, a track, a longitudinally extending ridge on the upper face and a groove in the lower face thereof, a carriage above said track, a longitudinally extending ridge on the under face of said carriage, a series of balls on each side of said ridges and supporting said carriage means for retaining said balls in position in pairs on opposite sides of said ridges, straps on said carriage inclosing the latter and said track, a bar held by said straps beneath said track and having a groove in its upper face, a series of balls between said bar and carriage and engaged in the said grooves therein, and antifriction rollers arranged vertically and carried by said straps on opposite sides of said track and in rolling contact with the side faces thereof.

12. The ball-retainer described, consisting of side-plates, blocks extending between said plates and having their adjacent faces grooved, said plates and blocks forming a series of pockets, and balls of a diameter greater than the thickness of said blocks, received in said pockets.

13. The ball-retainer described, consisting of side-plates having recesses formed in their interior surfaces, blocks extending between said plates and having their adjacent faces grooved, said plates and blocks forming a series of pockets, and a pair of balls received side-by-side in each of said pockets.

In testimony that I claim the invention above set forth I affix my signature, in presence of two witnesses.

FRANK W. S. ELSTROTH.
